(57) **CLAIM**

The ornamental design for a mop head, as shown and described.

DESCRIPTION

FIG. 1 is a top plan view of a mop head showing our new design;

FIG. 2 is a bottom plan view thereof;

FIG. 3 is a right side elevation view thereof of which the left side elevation view is a mirror image;

FIG. 4 is a rear elevation view thereof; and,

FIG. 5 is a top isometric view thereof.

Features of the drawing figures shown in dashed lines are for illustrative purposes only and form no part of the claimed design.
